UNITED STATES PATENT OFFICE.

LUDWIG LINKOWSKI, OF ALDENBOCHUM, GERMANY.

JIG-CONVEYER MOTOR.

Application filed November 9, 1920. Serial No. 422,954.

(GRANTED UNDER THE PROVISIONS OF THE ACT OF MARCH 3, 1921, 41 STAT. L., 1313.)

To all whom it may concern:

Be it known that I, LUDWIG LINKOWSKI, a citizen of Germany, and resident of Altenbochum, in the Republic of Prussia, Germany, have invented certain new and useful Improvements in Jig-Conveyer Motors (for which patents have been applied for in the following countries and on the following dates: Germany, August 20, 1918, Patent No. 326,505; German-Austria, September 17, 1919; Hungary, October 3, 1919, Patent No. 78,145; France, October 6, 1919, Patent No. 504,604; Holland, October 8, 1919, Patent No. 6343; Poland, November 4, 1919; Belgium, November 7, 1919, Patent No. 283,247; Czechoslovakia, December 18, 1919; England, December 6, 1919, Patent No. 136,177), of which the following is a specification.

My present invention relates to jig-conveyer-motors actuated by compressed air or the like and having no flywheel; but more particularly to novel means for controlling the supply, cut-off and exhaust of the driving-agent in such a manner that the ratio of expansion is maintained when the supply is changed.

In this kind of motor for jig-conveyers the stroke of the piston is not limited by a crank and the piston is cushioned until it is finally stopped by means of compression or by an advanced admission or lead of the driving-agent into the working-cylinder.

This retarded travel is a deliberately introduced feature of the conveyer design, on which, in the best known type of conveyers, used mainly in mining, the propulsion of the material depends. The propulsion is due to the fact that by virtue of the acceleration imparted to it, the material jumps forwards on the retarded run-way, whether the same is actuated by a double-acting or by a single-acting motor.

Generally the arrangement is such that the run-way of the conveyer has a drop, due to inclined or curved roller paths, and is lifted by the motor in the direction opposed to the direction in which the material is conveyed. The motor, particularly in mining practice, accordingly has to deal with a very much varying load. This load varies with the charge on the conveyer and with the length thereof, which may be increased or shortened according to the progress of the work,

and also with the angle of fall at which the conveying is performed. But as the load increases, the inertia to be overcome by the cushioning referred to also increases. This makes it necessary for the motor to be always adjusted for the maximum load, otherwise the brake effect at the end of the return stroke may be insufficient, allowing the piston to crash against the cylinder head and destroy it. But with the adjustment made for the maximum load to be dealt with in the course of a particular operation, it follows that when the load falls short of this, the piston is retarded too soon, and its stroke is shortened so that a large waste space is created, inasmuch as the volume of driving fluid enclosed in this space at the moment of the piston reversal is exhausted at the next stroke without having done any appreciable amount of work.

These conditions appear most clearly when the working of a single-acting motor is considered. With such a motor the piston lifts the conveyer during the forward stroke, and during the return stroke it is moved by the falling conveyer through a distance depending on the extent to which the inertia can overcome the brake effect.

The object of the invention is to make the conveyer motor regulatable by means of the valve control, so that in combination with the known regulation of the cut-off there is a regulation of the length of the cushioning path, the regulating device for the cut-off being connected in one with the regulating device for the cushioning by compression and advanced admission.

In motors where the adjustment is effected in the well known manner by means of tappets adjustable on, or in the direction of, the piston rod, the combination of the regulating devices may be effected by duplicating the tappet so that it actuates a single valve gear with one of its faces for admission and with its other face for cutting off admission.

In motors of the kind referred to, it is, however, necessary to utilize the driving pressure as efficiently as possible, which can only be done by utilizing expansion. For this purpose it is well known to make the valve gear adjustable so that expansion begins after the requisite cylinder filling, and exhaust at the end of the piston stroke. For

example, the tappets adjustable for this purpose in the direction of the piston path are so arranged that the filling is regulated by means of an adjustable tappet, the expansion tappet being shifted to the same extent. This has the disadvantage that the per cent of cut-off and the utilization of expansion, are changed, because if the supply is increased the piston works correspondingly longer under full charge. This extension must be subtracted from the expansion path, which is shortened, whereas properly it should be lengthened in accordance with the increased supply, to maintain the ratio (for example 1:4) in other words, the driving agent passes out at the exhaust with unnecessary high pressure.

If, as is also well known, the exhaust tappet is made adjustable independently of the cut-off tappet, by a separate device, the motor must be attended by a skilled hand, and this is rarely or never possible under ground.

This difficulty is met by the invention, by arranging that the movement of the exhaust tappet is made dependent on that of the cut-off tappet, so that the movement of the exhaust tappet is a definite multiple of the movement of the cut-off tappet. In this way the exhaust is postponed by shifting the exhaust tappet.

What has been stated with reference to tappets applies equally to any device for regulating the valve gear. If tappets are used, adjustable on, or in the direction of, the piston rod, it is convenient to obtain the governed connection of the supply and expansion tappets by providing the tappet actuating spindle with two screw threads of different pitches, the exhaust tappet being adjusted on a screw whose ratio, in reference to the other screw, equals the ratio of supply. This construction has the advantage that the regulation of the motor is effected by a single manipulation, which can be performed by an unskilled hand.

The invention is illustrated in the drawing by way of example as applied to a single-acting motor regulated by means of tappets adjusted by a screwed spindle in the piston rod.

In the accompanying drawing:—

Figure 1 is a longitudinal section of the motor, with the slide valve in position for admission,

Figure 2 is a similar section with the slide valve in cut-off position; Figure 3 is a side elevation, with parts in section, showing the motor in connection with the jig-conveyer, the slide valve being in the exhaust position, and the cams or tappets in a position of longer cut-off than in Figs. 1 and 2; and Figure 4 is a plan view of the motor, with the conveyer removed, the cams or tappets being in the same position as in Fig. 3.

In the motor cylinder *a* moves the piston *b* with its rod *c*, the thrust of which is transmitted by the crosshead *d* slide rods *p*, cross-head *q*, and connecting rod *r* to the conveyer *C*, see Figs. 3 and 4. The control is effected by a slide-valve *e* actuated by a lever *f*, which is moved by a rod *g* and rollers *h* and *i*. In the hollow piston rod is a spindle *k*, which can be turned by a handle *l*. On the spindle *k* are two tappets, namely, a two-faced tappet *m* and an ordinary tappet *n*. The tappet *m* striking the roller *h* with its upper face, regulates the admission. When the piston, under the weight of the conveyer, moves from right to left, the lower step of the tappet *m* sets the valve *e* to close the cylinder space behind the piston and compression begins (Fig. 2); then the roller *h* runs over the incline, so that advanced admission or cushioning is prepared, until when the roller *h* has reached its highest position, at which time the supply port *o* is opened fully. The piston at this moment has reached the position shown in Fig. 1 of the drawing, and begins its working or forward stroke. The other face of the tappet *m* now comes into action. The roller *i*, which must move with the roller *h* owing to a positive connection between them, is forced downwards by the lower inclined surface of the tappet *m*. (Fig. 2). By this means the supply port *o* is closed, and expansion begins. This continues until the roller *i* meets the inclined surface of the tappet *n* whereby it is further depressed and sets the valve *e* for exhaust (Figs. 3 and 4).

By turning the spindle *k*, the two tappets *m* and *n* can be moved from the extreme right hand position illustrated towards the left. By this movement of the tappet *m*, the opening of the supply port is effected earlier. The retardation path at the end of the return stroke is thus lengthened, and the cushioning or brake effect increased. This turning of the spindle is, therefore, effected when the load increases.

Owing to the shaping of the tappet *m* as supply tappet on top and as cut-off tappet at the bottom, the shifting of this tappet toward the left causes the closing of the supply port *o* to take place later, so that a larger supply is effected corresponding to the increased load. Both tappets *m* and *n* have internal screw threads fitted to the screw spindle, and are guided by the piston rod *c* in such a manner that the said tappets can move lengthwise of said rod, but can not turn relatively thereto.

The tappet *n* moves on a different part of the spindle from the tappet *m*. This part *k'* has a steeper screw thread, so that when the spindle *k* is turned as described the tappet *n* is moved through a greater distance towards the left than the tappet *m*. This is in accordance with the following

considerations. While the screw threads actuating the tappets *m* and *n* respectively are of different pitch, they are of the same direction, that is, both left-handed or both 5 right-handed.

When the tappet *m* is set for increased supply, by shifting it to the left, and expansion is to take place in same proportion as before when the supply was smaller, say 10 1:4, the face of the tappet *n* must come into action so much later as the path is shortened by the full supply (shifting of tappet *n*) plus the path required for the expansion of the increased supply. The ratio of the 15 pitches of the screw threads on the two parts of the spindle must be chosen accordingly.

The remainder of the piston stroke is of course shortened as compared with the extreme tappet adjustment for the smallest 20 supply. This remainder is performed by virtue of the swing of the conveyer, and it is entirely in accordance with the governing idea that this path is shorter, as the new setting of the tappets gives an increased 25 advanced supply, so that in the shorter path the cushioning or brake effect is increased in accordance with the greater inertia of the conveyer.

I claim:—

30 1. A motor suitable for jig-conveyers, said motor comprising a cylinder, a piston movable therein, a valve controlling the admission and exhaust of motive fluid to and from said cylinder, a valve-gear, means actuating said valve-gear to set said valve successively for the admission and for the cut-off, means actuating said valve-gear to set said valve for the exhaust, a regulating device adapted to secure automatically the 35 same ratio of expansion for every per cent of cut-off, and means for actuating said regulating device during the operation of the motor.

40 2. A motor suitable for jig-conveyers, said motor comprising a cylinder, a piston movable therein, a tubular piston rod, a valve controlling the admission and exhaust of motive fluid to and from said cylinder, a valve-gear, a tappet having two working-faces adapted to engage said valve-gear alternately to set said valve successively for the admission and for the cut-off, another tappet having a working-face adapted to engage said valve-gear to set said valve for the exhaust, a regulating device engaging 45 said tappets with screw-threads of like direction but different pitch, for imparting to said tappets linear movements of different extent, and means for actuating said regulating device from without.

50 3. A motor suitable for jig-conveyers, said motor comprising a cylinder, a piston movable therein, a tubular piston rod, a slide-valve controlling the admission and exhaust of motive fluid to and from said cylinder,

55 der, a valve-gear, a two-faced tappet carried by said piston rod and adapted to engage said valve-gear with one face to set said valve for the admission and with the other face for the cut-off, another tappet likewise 70 carried by said piston rod and adapted to engage said valve-gear to set said valve for the exhaust, a regulating screw-spindle engaging said tappets with screw-threads of like direction but different pitch for imparting a linear movement to said two-faced tappet and simultaneously imparting to the other tappet a linear movement in the same direction as the two-faced tappet but of 75 greater extent, and means for rotating said regulating screw-spindle.

80 4. A motor suitable for jig-conveyers, said motor comprising a cylinder, a piston movable therein, a tubular piston rod, a slide-valve controlling the admission and exhaust of motive fluid to and from said cylinder, a valve-gear, rotary engaging members carried by said valve-gear above and below the piston rod respectively, a two-faced tappet adapted to engage with 85 one face the upper of said engaging members to set said slide-valve for admission, and with the other face the lower of said engaging members to set said slide-valve for the cut-off, a one-faced tappet adapted 90 to engage said lower engaging member to set the valve for the exhaust, a screw-spindle engaging said tappets with threads of like direction but different pitch for imparting to said one-faced tappet a linear movement 95 which is a multiple of the movement imparted at the same time and in the same direction to said two-faced tappet, and means for rotating said screw-spindle from without.

100 5. A motor suitable for jig-conveyers, said motor comprising a cylinder, a piston movable therein, a slotted tubular piston rod, a slide-valve controlling the admission and exhaust of the motive fluid to and from said cylinder, a valve-gear, rollers carried by said valve-gear above and below said piston rod respectively, a two-faced tappet carried by said piston rod and slidable thereon, and adapted to engage said rollers alternately 105 to set said valve successively for the admission and for the cut-off, a one-faced tappet likewise carried by said piston rod slidably, said second tappet being arranged between the piston and the first-named tappet and being adapted to engage the lower roller to set said slide-valve for the exhaust, a regulating device for imparting to said two-faced tappet and simultaneously to said one-faced tappet a movement in the same direction but of greater extent for the one-faced tappet, and means for operating and regulating device from without.

110 6. A motor suitable for jig-conveyers, said motor comprising a cylinder, a piston

movable in said cylinder and adapted to move in one direction under the action of a motive fluid and to perform its return stroke without the driving action of such motive fluid, a tubular piston rod, a slide-valve controlling the admission and exhaust of such motive fluid to and from one end of said cylinder, a valve-gear, a tubular piston rod, a combined admission and cut-off tappet 5 cooperating with said valve-gear to set said valve successively for the admission and for the cut-off, another tappet cooperating with said valve-gear to set said valve for the exhaust, an adjusting screw-spindle having 10 two screw-threads of different pitch engaging said tappets to impart, for a given amount of rotation of said spindle, a greater linear movement to said exhaust-controlling tappet than to said combined admission and 15 cut-off tappet, and means for rotating said spindle from without during the operation 20 of the motor.

7. A motor suitable for jig-conveyers, said motor comprising a cylinder, a piston movable therein, a valve controlling the admission and exhaust of motive fluid to and from said cylinder, a valve rod, a tubular piston rod, guide bars arranged laterally of said piston rod; rollers carried by said guide bars 25 and arranged on opposite sides of said piston rod, a two-armed lever mounted on said cylinder pivotally and operatively connected at one end with said valve rod and at the other end to said guide bars, a two-faced tappet 30 adapted to engage the roller on one side of said piston rod, for operating the valve to begin the admission of motive fluid, and also adapted to engage the roller on the opposite side of the piston rod, for operating 35 said valve to cut off the supply of motive fluid, another tappet adapted to engage said last-named roller, for shifting said valve to the position in which it opens the exhaust, an adjusting screw-spindle having two 40 screw-threads of different pitch engaging 45 the respective tappets, the thread engaging the exhaust-controlling tappet being of steeper pitch than the one engaging the other tappet, a handle for rotating said spindle, and a cross head carried by said piston rod and adapted to transmit power 50 from said motor to the jig-conveyer.

8. An operating device comprising a cylinder, a piston movable therein, valve mechanism for successively admitting a motive fluid to said cylinder, cutting off the admission of such fluid and allowing it to act expansively, and finally allowing such fluid to escape from the cylinder, operating mechanism for said valve mechanism, said operating mechanism being connected with the piston to move therewith, and comprising two members one of which controls the admission and the cut-off of the motive fluid, while the 55 other controls the exhaust, and a screw- 60

spindle likewise connected to move with said piston and having screw-threads of like direction but of different pitch in engagement with the respective members of said operating mechanism, so that rotation of said 70 spindle will adjust both members in the same direction unequally, but at a constant ratio, whereby the expansion ratio may be kept constant.

9. An operating device comprising a cylinder, a piston movable therein, valve mechanism for first admitting a motive fluid to said cylinder, then cutting off the admission to allow such fluid to act expansively, and finally allowing such fluid to exhaust from the cylinder, actuating mechanism for said valve mechanism, said actuating mechanism including two members one of which controls the admission of the motive fluid and the cut-off, while the other controls the exhaust, and a unitary adjusting device operatively connected with said members and arranged to move both of them simultaneously in the same direction but to a different extent. 80

10. An operating device comprising a cylinder, a piston movable therein, valve mechanism for first admitting a motive fluid to said cylinder, then cutting off the admission to allow such fluid to act expansively, and finally allowing such fluid to exhaust from the cylinder, actuating mechanism for said valve mechanism, said actuating mechanism including two members one of which controls the admission and the cut-off of the 95 motive fluid, while the other controls the exhaust, and a unitary adjusting device operatively connected with said members and arranged to shift them simultaneously to a different extent in such a proportion as to 100 maintain a constant expansion ratio.

11. An operating device comprising a cylinder, a piston movable therein, a tubular piston rod, valve mechanism for first admitting a motive fluid to said cylinder, then cutting off the admission to allow such fluid to act expansively, and finally allowing such fluid to exhaust from said cylinder; two tappets movably arranged in said tubular piston rod, for actuating said valve mechanism, one of said tappets controlling the admission and the cut-off of the motive fluid, while the other tappet controls the exhaust; and an adjusting spindle engaging said tappets with screw-threads of different pitch to 110 move both of said tappets simultaneously in the same direction but to a different extent. 115

12. An operating device comprising a cylinder, a piston movable therein, a tubular piston rod, a valve, valve-operating mechanism adapted to set said valve first for admitting a motive fluid to said cylinder, then cutting off the admission to allow such motive fluid to act expansively, and finally allowing such fluid to exhaust from said cylinder. 125

inder, two tappets arranged in said tubular piston rod, for actuating said valve-operating mechanism, one of said tappets having a face for bringing said valve-operating mechanism to the position in which the motive fluid is admitted to the cylinder, and a face, on the opposite side of the tappet, for bringing said valve-operating mechanism to the cut-off position, while the other tappet 10 sets said valve-operating mechanism for the exhaust; and an adjusting spindle journaled in said tubular piston rod and engaging said tappets with screw-threads of like direction but different pitch, to impart, for a given 15 amount of rotation of said spindle, a greater linear movement to said exhaust-controlling tappet than to the other tappet, and to maintain a constant expansion ratio.

13. An operating device comprising a cylinder, a piston movable therein, valve-mechanism controlling the cut-off of the motive fluid and its exhaust from said cylinder, an adjustable member for varying the time of

the cut-off, another adjustable member for varying the time of exhaust, an operative 25 connection extending from one of said members to the other and engaging both of them with actuating portions of unlike character to cause said connection to adjust said two members simultaneously, but to different 30 extents.

14. An operating device comprising a cylinder and a piston therein, one movable relatively to the other, an adjustable member having operative connections to vary the 35 time of the cut-off of the motive fluid, another adjustable member for varying the time of the exhaust, and an adjusting member having unlike actuating portions engaging both of said members simultaneously 40 and arranged to adjust said members at the same time, to different extents bearing a constant ratio to each other.

Signed by me at Altenbochum, Germany, this 21st day of June, 1920.

LUDWIG LINKOWSKI.
